DESIGN FOR A SHOE

Mabel Julianelli and Charles A. Julianelli,
New York, N. Y.

Application November 12, 1942, Serial No. 108,756

Term of patent 7 years

To all whom it may concern:

Be it known that we, Mabel Julianelli and Charles A. Julianelli, both citizens of the United States of America, residing in the city, county, and State of New York, have invented a new, original, and ornamental Design for a Shoe, of which the following is a specification, reference being had to the accompanying drawing, forming part thereof.

The figure on the drawing is a side perspective view of a shoe showing our new design.

The dominant feature of our design resides in the portions shown in solid lines.

We claim:

The ornamental design for a shoe, substantially as shown and described.

MABEL JULIANELLI.
CHARLES A. JULIANELLI.
